(57) **CLAIM**

The ornamental design for a foldable trowel, as shown and described.

DESCRIPTION

FIG. 1 is a perspective view of a foldable trowel showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plain view thereof;

FIG. 7 is a bottom plain view thereof; and,

FIG. 8 is a top plan view of an embodiment of the foldable trowel, wherein the handle is folded and abuts a working piece of the foldable trowel of my new design.
